UNITED STATES PATENT OFFICE.

DUANE H. CHURCH, OF NEWTON, MASSACHUSETTS.

MACHINE FOR GAGING JEWELS.

SPECIFICATION forming part of Letters Patent No. 745,417, dated December 1, 1903.

Application filed November 12, 1898. Serial No. 696,193. (No model.)

To all whom it may concern:

Be it known that I, DUANE H. CHURCH, of Newton, in the county of Middlesex and State of Massachusetts, have invented certain new and useful Improvements in Machines for Gaging Jewels, of which the following is a specification.

This invention has for its object to provide a machine for automatically gaging or measuring the apertures in the jewels in which the pivots of the balance-wheels or other rotary or oscillatory parts of a watch are journaled. Heretofore this operation has been performed by hand, and by reason of the delicacy of the parts employed it has been exceedingly difficult to accomplish the gaging of the jewels in a satisfactory and sufficiently-expeditious manner. The pivots vary in diameter by reason of its being practically impossible to turn and polish them to the same extent, and hence it is necessary to ascertain the diameters of the apertures in the jewels, so that they may be selected to fit the pivots with the greatest possible accuracy.

In the embodiment of the invention which I have elected to illustrate the jewels are fed one by one to the action of the gaging or measuring devices, and after the diameter of the aperture in each is ascertained it is automatically placed in a receptacle and in a compartment reserved for jewels all having that internal diameter. The receptacle for the jewels is divided into compartments corresponding in number to the gages or measuring devices, and as the latter are brought one by one into operative relation to the jewel the receptacle is automatically advanced to bring the proper compartment into position to receive a jewel when a gage corresponding to the aperture therein has been reached. The gages consist of a series of spindles each having a pin different in diameter from the preceding one by a fraction of .001 part of a centimeter, and they are presented one by one to the jewel until a pin is reached which corresponds in diameter to the aperture in the jewel, whereupon the jewel is immediately deposited in a proper compartment, this being accomplished by pneumatically-operated mechanism regulated by a feeler mounted in operative relation to the gages. As soon as the jewel has been meas-

ured or gaged and the jewel-carrier has been advanced one step the gages and the jewel-receptacle are immediately returned to their initial or starting point and the operation of gaging the next jewel is begun. The jewels are stacked in a chute and are fed automatically to the jewel-carrier, so that the attendance of an operative except for the purpose of replenishing the chute is practically unnecessary.

Reference is to be had to the accompanying drawings, and to the letters marked thereon, forming a part of this specification, the same letters designating the same parts or features, as the case may be, wherever they occur.

Of the drawings, Figure 1 represents in plan view a machine embodying the invention. Fig. 2 represents a front elevation of the same. Fig. 3 represents a longitudinal section looking from the rear. Fig. 4 represents a transverse section on the line 4-4 of Fig. 2. Fig. 5 represents a detail sectional view, on a larger scale, showing the jewel-carrier, the gages, and the gage-carrier. Figs. 6 and 7 illustrate the feeler, which coacts with the gages. Fig. 8 represents in sectional view a portion of the receptacle and a portion of the gage-carrier. Figs. 9, 10, and 11 illustrate the gages greatly magnified and show the manner of utilizing the gages for measuring the diameters of the jewels. Fig. 12 illustrates more or less conventionally the ports for the passage of air to the various cylinders in the machine. Fig. 13 is a diagrammatic view of the electric circuits and the operative parts affected thereby.

Referring to the drawings, *a* indicates the base-plate, upon which a superstructure is mounted, the latter comprising end walls *a'*, a rear wall *a''*, and a top plate *a'''*. A shaft *b*, which I term the "cam-shaft," is journaled in the bearings in the end walls *a'* and is provided with a worm-wheel *b'*, to which motion is imparted from a worm *b''* on a shaft *b'''*, rotated by any suitable source of power. The shaft *b'''* is mounted in bearings supported upon the base-plate *a* and extending rearwardly from the end of the machine.

The jewels to be measured or gaged are shown greatly magnified in Figs. 9, 10, and 11, being indicated at *A*, and are mounted in settings *B*, which are of the same external di-

ameter. The jewels are stacked in a vertical chute c , mounted in sleeves c' , supported by a bracket or stand c^2 , extending upwardly from the top plate a^3 . The jewel-carrier 5 consists of a ring having a thin flat outer edge d , provided with a series of apertures d^2 , adequate to receive the settings B. The ring is detachably secured to a disk d^3 , keyed to a vertical shaft d^4 and held against removal 10 therefrom by the screw d^5 , passed into the end of the shaft. The disk d^3 is provided with an aperture d^6 at its edge to receive a dowel-pin d^7 , depending from the ring d , and it is mounted in a recess d^8 in the top of 15 the support d^9 . As the jewels drop into the apertures d^2 in the ring d they are prevented from falling therethrough by the block d^9 , upon which they rest and around the surface of which they are carried by the ring d , said 20 block having an aperture d^{22} , (see Fig. 8,) with which each aperture d^2 is adapted to register when it moves from the measuring position. The vertical shaft d^4 projects below the plate a^3 and is formed or provided 25 with a ratchet-wheel d^{10} , (see Fig. 5,) with which a pawl d^{11} is maintained in engagement by a spring d^{12} . The last two mentioned parts are shown in dotted lines in Fig. 1.

The pinion d^{13} is placed loosely upon the 30 shaft d^4 and is frictionally engaged therewith, there being a collar d^{14} secured to the end of the shaft by a screw d^{15} , and friction-rings d^{16} are interposed between the pinion d^{13} and the ratchet-wheel d^{10} and the said pinion and 35 the said collar d^{14} . To increase the friction, springs d^{17} are placed in sockets in the collar d^{14} and bear against a ring d^{18} , interposed between the collar and the friction-ring d^{16} next adjacent thereto. Consequently if the pinion d^{13} be turned in the direction of the arrow 2 in Fig. 1 the shaft and jewel-carrier 40 will be likewise advanced; but when the pinion is turned in the opposite direction the shaft will be held against retrograde movement by the pawl d^{11} . The pinion d^{13} intermeshes with rack-teeth formed upon one side of a piston e , (see Figs. 1 and 5,) having its ends in cylinders e' , e^2 , formed in the top plate a^3 , as indicated in Fig. 4. Compressed 45 air is admitted to the cylinder e^2 through a duct e^3 , which leads from a valve-casing f , into which latter it passes through a duct f' from a suitable source, and it is delivered intermittently into the duct e^3 by the movement of the valve f^2 , against the end of which 50 extends a lever f^3 , fulcrumed upon a shaft f^4 , journaled in arms projecting upwardly from the valve-casing f . The upper end of the lever f^3 bears against a cam f^5 upon the 55 shaft b , having as many rises as there are gages, to be subsequently described. Consequently as there are twelve gages air is admitted into the cylinder e^2 twelve times for each rotation of the cam-shaft b . The piston 60 e is normally in its rearmost position, as shown in Figs. 1 and 4, so that the delivery

of the air into the cylinder e^2 ordinarily accomplishes no movement thereof.

The valve f^2 is double-acting and bears against a spring f^6 , inserted between its inner end and a plug f^7 , secured to the valve-casing. The rearward movement of the valve opens a passage-way from the duct f' into a duct e^4 , as shown in Figs. 3 and 4, which leads into a valve-casing e^5 , in which 75 is placed a vertically-moving valve e^6 . From the valve-casing another duct e^7 leads into the rear end of the cylinder e' . The valve e^6 is held normally against the pressure of a spring e^{81} to close communication between 80 the ducts e^4 and e^7 by a latch e^8 , whose lower hooked end projects under the lower end of the valve. To the upper free end of the latch is secured the armature e^9 of an electromagnet e^{10} , whose coil is in circuit with two 85 contacts e^{11} , e^{12} , the latter of which is a spring and normally bears against the other to keep the circuit closed. The electric circuit is indicated at e^{12} , as shown diagrammatically in Fig. 13. So long as these last-mentioned 90 parts are in contact the magnet is energized to attract the armature e^9 to it, and thereby hold the lower end of the latch underneath the lower end of the valve, whereby air is not permitted to pass from the duct e^4 into the 95 duct e^7 , and consequently the piston e remains stationary under ordinary conditions. When, however, a jewel has been gaged, the contact between the parts e^{11} , e^{12} is broken by devices which are to be subsequently described, whereupon the spring e^{81} forces down the valve e^6 , the latter being released by the latch, and the compressed air at the next movement of the valve f^2 is permitted to pass from the duct e^4 into the duct e^7 and 100 force the piston e forward to feed the jewel-carrier one step, and immediately thereafter a cam g on the cam-shaft b engages a lever g' , fulcrumed upon a stud in a bracket g^2 , and raises the rear end of the said lever, 105 which being under the valve e^6 lifts it to cut off the entrance of air into the duct e^7 , and the magnet e^{10} is energized to cause the latch e^8 to again engage the valve and prevent it from dropping. There are as many rises upon 110 the cam g as there are on the cam f^5 , so that the lever g' is constantly reciprocated for the purpose of raising the valve e^6 each time it drops, and the said rises are a little in advance of those on the cam f^5 , so that after 115 the valve e^6 has been raised the valve f^2 is shifted forward by the spring f^6 to permit compressed air to pass into the cylinder e^2 to thrust the piston e rearward.

The gage-carrier consists of a cylinder h , 120 rigidly secured by a screw h' to a shaft h^2 , journaled in bushings h^3 , h^4 , supported by a bracket h^5 and the top plate a^3 , respectively. A split nut h^{51} , having its ends connected by a set-screw h^6 , is screwed upon the upper 125 threaded end of the shaft, as shown in Fig. 5, and the lower end of the shaft is formed or

provided with a ratchet-wheel h^7 , abutting against the bushing h^4 , so that the shaft is held against axial movement. A gear-wheel h^8 is secured to the lower end of the shaft to turn therewith, there being also a screw h^9 , which holds it thereon. A pawl h^{10} on a stud depending from the top plate is held in engagement with the ratchet by a spring h^{11} , as shown in Fig. 1, and by means of mechanism to be described the gage-carrier is advanced step by step in the direction of the arrow 3, the pawl preventing it from moving backward and centering it relatively to the jewel-carrier and the jewel therein being measured.

The gages consist of minute cylindrical pins i , each extending downwardly from the holder i' , secured to a spindle i^2 , the upper end of which is headed at i^3 . These spindles are longer than the cylinder h and are arranged to slide in V-shaped grooves therein, being held in said grooves by a sleeve h^{13} , which has a slot registering with each spindle. Placed in each slot is a spring h^{14} , connected at its upper end to the spindle and at its lower end to the sleeve, whereby, if permitted, the spindles will all be drawn downward. The shaft h^2 is placed in such relation to the shaft d^4 that one of the gages i is always over one of the jewels in the jewel-carrier, and as the gage-carrier rotates step by step the gages are brought one by one into operative relation to the jewel. The diameter of each gage i is slightly greater than the preceding one, and after they are brought over the jewel they are depressed. So long as a gage can enter the jewel it is evident that it is smaller in diameter than the aperture in the jewel; but as soon as a gage is reached whose diameter corresponds to that aperture in the jewel and cannot enter therewith, inasmuch as the diameters of the gages are known, it can be easily ascertained what the diameter of the jewel is.

In order to effect the axial movement of the gages, I employ a pneumatic device consisting of a piston i^4 , arranged in the cylinder h and having a flange i^5 , which projects under the head i^3 of all of the gages. Air is admitted into the cylinder through a port i^6 , which extends through the shaft h^2 , the bushing h^4 , and the frame of the machine to the valve-casing f . The passage of air to the said ducts is controlled by a single-acting valve i^7 , practically similar to the valve f^2 , previously described, and against the forward end of which a lever i^8 bears. This last-mentioned lever is operated by a cam i^9 on the shaft b , and each time it is reciprocated the air is cut off from the cylinder h and the gages are allowed to drop.

Centered on a stud j^5 , supported upon a lateral extension of the bracket h^6 and in operative relation to the gages, is a curved lever j , (see Figs. 6 and 7,) having on its end a split bearing j^7 , through which the pin j^2 passes. A nut j^3 on the pin serves to adjust it and to raise

or lower its head j^4 relatively to the heads i^3 of the gage-spindles. The opposite end of the lever is adapted to engage the contact e^{12} and force it away from the contact e^{11} , being provided with a spring j^6 for this purpose. An arm k , secured to a rock-shaft k' , has a pin k^2 , which when the shaft k' is rocked is adapted to engage the lever j and move its free end outwardly against the pressure of the spring j^6 , said lever having a notch j^{10} , which permits the spring j^6 to move the lever so as to force its free end inward when the arm k is in the position shown in Fig. 7. The lower end of the shaft k' has an arm k^3 , with a pin k^4 , bearing against a peripheral cam k^5 upon the shaft b , and as the shaft rotates the shaft k' is rocked to vibrate the lever j .

I term the lever j , with the pin mounted in the end thereof, a "feeler," and it regulates the pneumatic device for the jewel-carrier, inasmuch as when the spring j^6 is permitted to force the free end thereof inward it breaks the contact between the two parts $e^{11} e^{12}$, and consequently effects a dropping of the valve e^6 to open communication between the ducts e^4 and e^5 .

The pin j^2 is so adjusted that its head j^4 is adapted to engage the head of the gage, which is directly over the jewel being measured, (unless the gage cannot enter in the aperture therein and is therefore held out of the path of the head j^4 of the pin j^2 ,) so that ordinarily the spring j^6 is unable to force the long end of the lever outward and break the contact between the parts $e^{11} e^{12}$. As soon, however, as a gage which corresponds in diameter to the aperture in the jewel reaches its position over the jewel being measured and is prevented from descending into engagement therewith and the shaft k' is rocked to disengage the pin k^2 from the lever j the head j^4 is free to move inward past the head i^3 of the pin, and the contact e^{12} is forced outward away from the contact e^{11} . The disengagement of the contact $e^{11} e^{12}$ accomplishes another result which shall subsequently be described.

The receptacle for the jewels is divided into as many compartments as there are gages, and each compartment is formed by a removable tray m' , into which are placed jewels having the same-sized apertures. The receptacle itself is secured to a sleeve m^2 , rigidly attached to the end of a vertical shaft m^3 , journaled in a removable bearing-block m^4 in the top plate and in a bearing-block m^5 on the bed-plate of the machine. The receptacle fits within a cylindrical socket in the top plate a^3 , and the edges of the trays project slightly above the surface of the latter, as shown in Fig. 3. Rigidly secured to the shaft m^3 is a gear-wheel m^6 , similar to and meshing with the previously-mentioned gear-wheel h^8 on the shaft h^2 . The shaft is also formed or provided with a ratchet-wheel m^7 just below the gear-wheel m^6 , and mounted loosely upon the shaft between the ratchet-wheel m^7 and the

collar m^8 , rigidly secured upon the said shaft, is a pinion m^9 . Between the pinion and the ratchet-wheel is placed a ring m^{10} , of friction material, such as rubber or other equivalent substance, and between the said pinion and the collar m^8 are placed a friction-ring m^{11} and a disk m^{12} , against the latter of which springs m^{13} in sockets in the collar m^8 bear. By means of the friction-rings and the springs 10 the pinion is engaged frictionally with the shaft, whereby if the pinion be turned the shaft will be turned therewith unless prevented by the engagement therewith of some stationary device. The movement of the said 15 shaft and pinion effects a step-by-step movement of the gage-carrier, so that the latter and the jewel-receptacle are advanced simultaneously.

Arranged in the cylinders n n' , which extend endwise of the machine, are two pistons n^2 n^3 , connected by a piston-rod n^4 , having rack-teeth n^{50} along one edge. Ducts n^5 n^6 extend into the outer ends of the cylinders from the valve-casing f , the admission of air 20 into the said ducts being controlled by a valve n^7 , similar in all respects to that shown in Fig. 4 and lettered f^2 . A lever n^8 , fulcrumed upon the shaft f^4 , bears against the valve n^7 at its lower end and at its upper end bears 25 against a cam n^9 on the shaft b , said cam having as many rises as the other cams. As the cam is rotated the valve is reciprocated to admit air first into one cylinder, as n , and then to the other cylinder, as n' , to provide 30 a reciprocation of the rack or piston-rod n^4 . The extent of movement of the piston-rod is limited by the valve e^6 , the upper end of which extends into a slot n^{10} in the under side of the piston n^3 , and thereby permits the pistons to 35 be reciprocated only the length of the slot so long as the valve is held in its raised position by the latch e^8 . The piston-rod n^4 is provided with a pin n^{11} in operative relation to the ratchet-wheel m^7 , as shown in Figs. 1 40 and 3. When the valve is raised and the pistons moved in the direction of the arrow 4 in Fig. 1, the rack engaging pinion m^9 turns it and the shaft therewith in the direction of the arrow 5 until the movement 45 of the piston n^3 is stopped by the valve e^6 . Then when the piston-rod n^4 is moved in the opposite direction the pawl h^{10} , engaging the ratchet h^7 , prevents a retrograde movement 50 of the gear-wheels h^8 m^6 , and at the end of the movement of the piston-rod n^4 the pin n^{11} 55 engages one of the teeth of the ratchet-wheel m^7 and turns it backward slightly to bring the teeth of the ratchet-wheel h^7 firmly against the end of the pawl h^{10} , so as to center a gage over the aperture in the jewel to be measured. 60 Now then when a jewel has been gaged and the feeler has broken the circuit through the electromagnet to cause the dropping of the valve e^6 and the consequent forward movement of the jewel-carrier air is admitted immediately thereafter into the cylinder n and

the pistons n^2 n^3 are driven their full stroke to cause the rack-teeth to turn the pinion m^9 in the direction of the arrow 5 until a pin n^{12} on the ratchet (see Fig. 1) engages a movable 70 stop consisting of the end of a piston-rod n^{13} . This piston-rod n^{13} projects out from a piston n^{14} in a cylinder n^{15} , connected by a duct n^{16} with the cylinder n . When the piston n^2 is in the position shown in Fig. 1, air cannot be 75 admitted into the cylinder n^{15} , as the duct n^{16} enters the cylinder n on the opposite side of the piston n^2 to that on which the duct n^5 enters, so that normally the piston-rod n^{13} is backed out of the way of the pin n^{12} when 80 the jewel-receptacle is being turned around step by step; but as soon as the piston n^2 is permitted to pass the mouth of the duct n^{16} the air is admitted under pressure to the cylinder n^{15} , and the piston n^{14} is forced forward 85 to cause the end of the piston-rod n^{13} to engage the pin n^{12} and stop the ratchet-wheel, and therefore the gage-carrier and the jewel-receptacle, at their initial or starting positions. The gages and the compartments or 90 trays in the receptacle are so related to each other, as has been previously stated, that when the jewel-receptacle has made one complete revolution the gage-carrier has done the same, and as each compartment or tray in the 95 receptacle is adapted to receive jewels having apertures of the same size consequently when a gage is directly over the jewel the compartment which receives jewels having apertures corresponding to that gage is in 100 position to receive the jewel at the next movement of the jewel-carrier. The block d^9 , on which the jewel-carrier turns, being provided with the aperture d^{25} , beneath which there is always one compartment of the jewel-receptacle and with which each aperture in the jewel-carrier registers immediately after the jewel therein has been measured, therefore 105 immediately after a jewel has been gaged it is dropped into the proper compartment. 110 The parts of the machine are so timed that when a gage has been reached which corresponds to the aperture in the jewel and the feeler is free to operate to break the circuit through the electromagnet the latch e^8 permits the valve e^6 to drop, and air is thereby 115 allowed to pass into the cylinder e' to feed the jewel-carrier one step forward, whereupon the jewel immediately drops through the aperture d^{25} into the compartment in the receptacle which is waiting to receive it and which corresponds to the gage that fitted the jewel. 120 Immediately after this compressed air is admitted to the cylinder n , and the jewel-receptacle and the gage-carrier are returned to 125 their original or starting points, as described, after which air is admitted to the cylinder n to return the pistons n^2 n^3 to their normal positions. Then the cam g , engaging the lever g' , raises the valve e^6 until it enters the aperture n^{10} in the pistons n^3 , and the latch e^8 130 engages its lower end. Then the jewel-re-

ceptacle and the gage-carrier are again advanced step by step until the first jewel, which is now in place, is measured.

While I have described my invention as being adapted for measuring the apertures in a series of jewels, yet any one skilled in the art will readily appreciate the fact that so far as the invention itself is concerned it may be embodied in machines for measuring or gaging objects of various kinds, either large or small, and that the various parts of the machine herein described may be modified or changed without departing from the spirit and scope of the invention.

Having thus explained the nature of the invention and described a way of constructing and using the same, though without attempting to set forth all of the forms in which it may be made or all of the modes of its use,

I declare that what I claim is—

1. A jewel-gaging machine having a chute for holding a plurality of jewels, means for automatically carrying the jewels from said chute and means for automatically gaging their apertures while held by said carrying means.

2. A machine of the character described, comprising gaging devices for gaging the apertures in jewels, and mechanism for separating the gaged work according to its measurement.

3. A machine for gaging the apertures in jewels, comprising gaging mechanism including a plurality of rods or pins varying in diameter adapted to be brought successively against the work with their axes in alinement with that of the hole, a receptacle having a series of compartments, and mechanism for distributing the gaged work into the compartments.

4. A machine of the character described, comprising a work-receptacle having a series of compartments, a series of graded gages one corresponding to each compartment, said gages being adapted to measure the diameter of an aperture in the work, and a carrier for the work, said parts operating to gage the work and place it in the compartment corresponding to the gage.

5. A machine for gaging the apertures in jewels, comprising a work-holder having means for holding the work temporarily against movement therein, a work-receptacle having a series of compartments, a series of aperture-gages, a carrier for the gages, and mechanism for moving the receptacle and carrier in unison.

6. A machine for gaging the apertures in jewels, comprising a work-holder having means for holding the work temporarily against movement therein, a series of graded aperture-gages, a carrier for said gages, mechanism for imparting a movement to said carrier until a gage is reached which corresponds with the work, and mechanism for returning the carrier to its starting-point.

7. A machine for gaging the apertures in jewels, comprising a work-holder having means for holding the work temporarily against movement therein, a series of graded gages, a carrier for the gages, a series of compartments for the work, mechanism for imparting a step-by-step movement to the carrier and the said compartments, and devices for returning said carrier and compartments to their starting-points.

8. A machine of the character described, comprising a work-holder, a series of graded gages, a carrier for the gages, mechanism for imparting a step-by-step movement to the carrier, a feeler in operative relation to the gages, and mechanism controlled by said feeler for returning the said carrier to its starting-point.

9. A machine of the character described, comprising a work-holder, measuring devices for the work, a work-receptacle having a series of compartments, mechanism for imparting a step-by-step movement to the work-receptacle, a feeler in operative relation to the measuring devices, and mechanism controlled by said feeler for returning the work-receptacle to its starting-point.

10. A machine for gaging the apertures in jewels, comprising a series of graded aperture-gages, a work-carrier adapted to hold the work stationarily therein while it is being measured, and mechanism controlled by the gages for feeding the work-carrier.

11. A machine for gaging the apertures in jewels, comprising a series of graded aperture-gages, a work-carrier, a receptacle for the measured work, and mechanism controlled by the gages for causing the work-carrier to drop its work in the said receptacle.

12. A machine of the character described comprising measuring devices, a receptacle for the measured work, a carrier for the work, a feeler in operative relation to the measuring devices, and mechanism controlled by said feeler for feeding the carrier to present a fresh piece of work to the gages, and to drop the measured work in the receptacle.

13. A machine of the character described comprising measuring devices, a movable receptacle having compartments for the measured work, a movable gage-carrier having a series of gages, a movable work-carrier, a feeler, and mechanism controlled by said feeler for advancing the work-carrier, and returning the gage-carrier and work-receptacle to their starting-points.

14. An organized machine comprising a carrier for the work, devices for automatically feeding the work thereto, measuring devices, a movable receptacle, and mechanism for separating the work according to its grade or measurement into said movable receptacle.

15. An organized machine comprising a feeding device, a work-carrier, a gage-carrier having a series of graded gages, a movable work-receptacle having a series of compartments

ments, and power devices for causing the work to be presented to the gages to be measured and then placed in its proper compartment.

5 16. An organized machine comprising a feeding device, a work-carrier, a gage-carrier having a series of graded gages, a movable work-receptacle having a series of compartments, and electropneumatic mechanism for

causing the actuation of all of said elements, to cause the work to be measured and deposited in the proper receptacle.

In testimony whereof I have affixed my signature in presence of two witnesses.

DUANE H. CHURCH.
